WORK HOLDING FIXTURE

Aldege L. Dery, Pine Meadow, Conn.

Application June 12, 1945, Serial No. 599,077

4 Claims. (Cl. 90—60)

1

This invention relates to improvements in work holding fixtures and more particularly to the type of fixture used in connection with milling operations. Such devices are commonly employed on milling machines to hold work pieces to be milled though they may be employed for other operations such as grinding.

The object of the invention is rigidly to support one or more work pieces in position for a machine operation and to prevent its displacement as a result of the forces applied thereto.

Another object is a gang fixture in which a plurality of pieces may be held and firmly clamped during a machine operation.

Among its features, my invention embodies a plurality of jaw members supported by a fixed jaw, each of which is provided with a pair of angular faces at one end, and a movable jaw adapted to be advanced toward the fixed jaw and the jaw members to clamp work pieces between the angular faces of adjacent jaw members and the fixed jaw whereby a three point support is provided for each work piece.

Other features embody relieving the jaw members in such a manner that the work pieces are engaged by a slightly yielding pressure so as to compensate for slight irregularities occurring in the sides of the work pieces which are engaged by the faces of the jaw members and the movable jaw.

Still other features embody the use of resilient jaw members or resilient clamping members which cooperate with the jaw members so as to produce a cushioned holding effect on the work.

In the drawings:

Figure 1 is a top plan view of a milling fixture designed for straight line work and embodying my invention;

Figure 2 is a transverse sectional view taken on the line 2—2 of Figure 1;

Figure 3 is a perspective view of a jaw member possessing the cushioning characteristics;

Figure 4 is a top plan view of a fixture adapted for use on a rotary milling machine and embodying my invention;

Figure 5 is a transverse sectional view taken on the line 5—5 of Figure 4;

Figure 6 is a detail perspective view of a resilient jaw member which may be used in conjunction with the fixture illustrated in Figure 4;

Figure 7 is a view similar to Figure 6 of a modified form of clamp jaw for use in conjunction with the type of fixture illustrated in Figure 4;

Figure 8 is a top plan view of a modified form of circular milling fixture;

2

Figure 9 is a transverse sectional view taken on the line 9—9 of Figure 8; and

Figure 10 is a perspective view of a modified form of jaw for use in connection with the fixture illustrated in Figure 8.

Referring to the drawings in detail, a milling fixture for use in straight line milling is designated generally 15 and comprises a fixed jaw 16 which is constituted of a U-shaped frame having at opposite ends legs 17. The ends of these legs are drilled and tapped to receive retaining bolts 18 by means of which a movable jaw 19 is supported in operative relation to the fixed jaw 16. Extending transversely through the legs 17 of the fixed jaw 15 are aligned openings 20 for the reception of a retaining bar 21, the purpose of which will be more fully hereinafter described. Extending through the bight portion 16 of the stationary jaw at spaced intervals are openings 22 for the reception of bolts 23, the inner ends of which enter screw threaded openings 24 in the rod 21 previously referred to.

Mounted between the arms 17 of the U-shaped frame of the fixed jaw 15 are jaw members designated generally 25. Each such jaw member comprises a body 26 opening through the upper edge of which is a slot 27 and opening through the lower edge of which is another slot 28. The rear wall of the slot 27 is formed with a recess 29 against the wall of which the rod 21 previously described is adapted to rest. When the jaw members 25 are in position within the fixed jaw 15 the rod 21 is thrust through the opening 20 and the slots 29 and the screws 23 are tightened to securely hold the rear or inner ends of the jaw members against the bight portion 16 of the fixed jaw 15 as illustrated in Figures 1 and 2. As shown in Figure 1, the forward ends of the jaw members 25 project beyond the ends 40 of the arms 17 of the jaw member 15, and these forward ends are formed with inclined faces 30 which are adapted to cooperate with the movable jaw 19 in clamping the work pieces W in position in the fixture. Each jaw member is relieved along one side as at 31 from a point intermediate their ends so as to allow a slight resilience to compensate for irregularity in the work pieces W. The slots 27 and 28 cooperate to allow the jaw members 25 to yield along its longitudinal axis 45 so that the work pieces W are clamped firmly in position under a slight yielding pressure longitudinally of the jaw members.

In the modification illustrated in Figures 4 and 5, the fixed jaw member designated generally 32 comprises a substantially ring-shaped body 33

having an upstanding flange 34 and an annular groove 35 at the junction of the body 33 with the flange 34. In this form of fixture the jaw members designated generally 36 are arranged radially so that the work pieces are held in a closed annular row.

Each jaw member 36 comprises a body 38 carrying at its lower rear end a tongue 39 which is adapted to seat in the annular groove 35 in order to lock the jaw member in place. A ring shaped cover plate 40 is attached to the upstanding flange 34 by suitable attaching means, such as screws 41 and overlies the upper faces of the jaw members 36 in order to hold them against accidental displacement. The end of each jaw member opposite the end carrying the tongue 39 is provided with a pair of inclined faces 42 which cooperate with the movable jaws to be more fully hereinafter described in clamping the work pieces W in the fixture. Like the previously described jaw members, each of the jaw members 36 is relieved along one side as at 43 to allow slight sideways motion in order to accommodate slight irregularities in the work pieces. As previously described, the body 33 is substantially ring-shaped in form and extending upwardly in concentric spaced relation with the flange 34 is a wall 44 which is provided with radial slots 45 in which movable jaw members 46 are adapted to slide. The slots 45 are so arranged that they align axially with the apices of the V-shaped grooves formed between adjacent jaw members 36, as will be clearly seen upon reference to Figure 4. As illustrated in Figure 5, each jaw member 46 is provided in its upper edge with a notch 47 for the reception of a compression coil spring 48, one end of which bears against the rear end of the recess 47, while the opposite end bears against a pin 49 carried by a cover plate 50, which is held in position on the annular wall 44 by means of fastening devices such as screws 51. As shown, the rear or innermost ends of the movable jaw members 46 are inclined as at 52 for engagement with a frusto conical block 53, which is mounted to move axially through the ring-shaped body 33. Closing the lower open end of the passage through the ring-shaped block 33 is a cover plate 54 having an internal screw threaded opening formed axially therein for the reception of a screw threaded shaft 55, the inner end of which is swivelly connected as at 56 to the frusto-conical member 53, while the outer end carries a suitable cross bar (not shown) by means of which the shaft 55 may be rotated within the opening in the plate 54 so as to advance or retract the frusto-conical block 53 axially through the body 33. It will thus be seen that as the block 53 advances the movable jaw members 46 will be projected toward the stationary jaw member 36 through the contact of the inclined walls 52 of the jaw members 46 with the surface of the conical member 53. In this way the work piece W will be clamped between the outer ends of the movable jaw members 46 and the inclined faces 42 of the stationary jaw members 36.

In Figures 6 and 7, I have disclosed certain modifications which may be incorporated in the device just described. The stationary jaw members for instance, as illustrated in Figure 6 and designated generally 57, may be formed with slots 58 and 59 in order to provide a certain amount of longitudinal resilience in the jaw members 57 which, it is to be understood, may be substituted for the jaw members 36. The functions of the

slots 58 and 59 is essentially the same as that of the slots 27 and 28 of Figure 3.

Alternately instead of providing the stationary jaw members with such slots, I may find it desirable to employ a jaw member such as that designated generally 60 with slots 61 and 62 in order to provide the desired resilience when its work clamping end 63 is moved positively outward into work engaging position. When such a movable jaw member is used, it is obvious that the conventional jaw member 36 will be employed in the fixture illustrated in Figures 4 and 5.

In Figures 8 and 9 I have disclosed a further modification of my invention corresponding in many respects to the structure illustrated in Figures 4 and 5, but provided with a different form of movable jaw advancing means. In this type of device a body 64 of substantially circular form is provided at its peripheral edge with an upstanding flange 65 and at the junction of the flange 65 with the body 64 is formed with an annular groove 66. Formed concentrically with the body but spaced inwardly from the flange 65 is an annular channel 67 adjacent the outer peripheral edge of which is a similar channel or groove 68 of somewhat lesser depth and about one-half of the width of the channel 67. Extending inwardly from the side wall of the body 64 and communicating with the channels 67 and 68 is a bore 69, the purpose of which will be more fully hereinafter described.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

Attached as by screws 70 to the body 64 concentric with the ring 65 is a disk 71 which is of a thickness substantially equal to the height of the wall or flange 65, which disk is provided with a plurality of radial grooves 72 in which movable jaws 73 are slidably mounted. Each of these jaws is provided with a depending lug 74 for a purpose to be more fully hereinafter described. Like the jaws 25 and 57, the jaws 73 may also be provided with vertical slots 75 and 76 so, if desired, a jaw 77 (Figure 10) having a depending lug 78 and in which the slots 75 and 76 are omitted may be substituted.

also obvious that jaw members of the type illustrated in Figure 6 may be used in conjunction with the jaw members 73, without in any way departing from the spirit and scope of this invention.

In operation, it is obvious that work pieces W introduced into the spaces between the movable jaw members or member, as the case may be, and the stationary jaw members of any one of the forms of the invention herein shown will be clamped firmly against dislodgment when the movable jaw member is advanced toward the stationary jaw members and each work piece will be suspended at three points. By reason of the release of the stationary jaw members, their free ends may move slightly from one side to the other in order to accommodate work pieces W having slight irregularities and that by the use of the resilient jaws or jaw members the work will be yieldingly yet firmly held in place when the movable jaw members are advanced into clamping position.

While in the foregoing there has been shown and described the preferred embodiment of this invention it is to be understood that minor changes in the details of construction, combination, and arrangement of parts may be resorted to without departing from the spirit and scope of the invention as claimed.

I claim:

1. A work holding fixture comprising a fixed jaw, a plurality of individual jaw members carried by the fixed jaw, a movable jaw, each jaw member comprising a substantially S-shaped body and having oppositely inclined work engaging faces at one end each of which cooperates with the movable jaw and a work engaging face of an adjacent jaw member in yieldingly clamping a work piece and means to advance the movable jaw toward the fixed jaw.

2. A work holding device comprising a fixed jaw, a plurality of individual jaw members carried by the fixed jaw, a movable jaw, each jaw member comprising a substantially S-shaped

body having oppositely inclined work engaging faces at one end each of which cooperates with the movable jaw and a work engaging face of an adjacent jaw member in clamping a work piece.

- 5 3. A work holding fixture comprising a fixed jaw, a movable jaw, a plurality of individual jaw members carried by the fixed jaw, each individual jaw member comprising an S-shaped body with its longitudinal axis disposed toward the movable jaw, the end of each individual jaw member facing the movable jaw being provided with at least two inclined work engaging faces whereby when the movable jaw is advanced toward the fixed jaw work introduced into the fixture will be yieldingly clamped between the inclined faces of two adjacent jaw members and the movable jaw.
- 10 4. A work holding fixture comprising a fixed jaw, a movable jaw, a plurality of individual resilient S-shaped jaw members carried by the fixed jaw, each such jaw member having inclined work engaging faces each of which cooperates with the movable jaw and work engaging face of the next adjacent jaw member in yieldingly clamping a work piece.
- 15 20 25
